UNITED STATES PATENT OFFICE.

JOHN STAGG, OF PATERSON, NEW JERSEY, AND ARTHUR H. SPEAR, OF NEW YORK, N. Y.

DESIGN FOR A HARNESS-HANGER HOOK.

SPECIFICATION forming part of Design No. 34,114, dated February 19, 1901.

Application filed January 24, 1901. Serial No. 44,634. Term of patent 7 years.

To all whom it may concern:

Be it known that we, JOHN STAGG, of Pater-
son, in the county of Passaic and State of
New Jersey, and ARTHUR H. SPEAR, of the city
5 of New York, borough of Manhattan, in the
county and State of New York, citizens of
the United States, have invented and pro-
duced a new and original Design for a Har-
ness-Hanger Hook, of which the following is
10 a full, clear, and exact description.

Reference is to be had to the accompanying
drawing, forming a part of this specification,
in which the figure is a perspective view of a
harness-hanger hook, illustrating our design.

15 The leading feature of the design for a har-
ness-hanger hook consists in an elongated
body portion having tongues at the ends,
the said tongues being inclined upward and
outward.

20 Adjacent to the lower tongue a perforation

is shown, and the upper tongue is somewhat
longer than the lower tongue.

Having thus described our invention, we
claim as new and desire to secure by Letters
Patent—

25 The design for a harness - hanger hook, as
herein shown and described.

In testimony whereof we have signed our
names to this specification in the presence of
the subscribing witnesses.

JOHN STAGG.
ARTHUR H. SPEAR.
